BY

Louis Necko
ATTORNEY.

UNITED STATES PATENT OFFICE

CHESTER S. IVORY, OF PHILADELPHIA, PENNSYLVANIA, ASSIGNOR TO THE ESTATE OF
J. W. IVORY, OF PHILADELPHIA, PENNSYLVANIA

TOOTH SEPARATOR

Application filed April 27, 1931. Serial No. 533,044.

My invention relates to a new and useful tooth separator, the same being an improvement on my prior Patent #1,702,869 of February 19th, 1929. The general purpose and the advantages of my invention are fully set forth in my said patent, but I have found that the structure therein disclosed and claimed could be improved upon in two respects. First, in my prior construction it is necessary to separate the inner jaws of my tooth separator, that is the jaws that bear upon the inner surface of the teeth, by means of a threaded element and this consumed unnecessary time, and I have therefore invented a new construction whereby said jaws could be set by hand to any desired adjustment after which the gradual separating by means of the threaded element could be accomplished. Second, in my prior construction the outer jaws, that is, the jaws that bear on the outer surface of the teeth, were individually adjustable by means of a threaded element which by nature of the construction was located in close proximity to the gums and the lips so that manipulation of said outer jaws was rather difficult, and I have invented a new construction whereby said threaded elements are dispensed with.

It is the object of my present invention to eliminate these disadvantages and to provide a tooth separator, the jaws of which could be set by hand to any desired adjustment prior to the application of gradual pressure by means of the threaded element which forces the jaws apart to bring a separating action to bear upon the teeth to be affected.

To the above ends my invention consists of an inner pair of hooked jaws, pivoted at their outer ends to a common link, a threaded element engaging said link, a toggle connection adapted to be operated by said threaded element, a pair of slotted brackets carried by said jaws, and an outer pair of jaws adapted to slide in said brackets and to be actuated by said toggle connection.

My invention further consists of various other novel features of construction and advantage all as hereinafter described and claimed in the drawings, in which:

For the purpose of illustrating my inven-

tion, I have shown in the accompanying drawings one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of the instrumentalities as herein shown and described.

Fig. 1 represents a plan view of a tooth separator embodying my invention shown applied to the separation of two contiguous teeth.

Fig. 2 represents a view similar to Fig. 1 showing my novel tooth separator applied to the separation of two non-contiguous teeth.

Fig. 3 is a section on line 2—2 of Fig. 1.

Fig. 4 represents a perspective view of one of the inner jaws forming part of my tooth separator.

Fig. 5 is a plan view of one of the outer jaws which form part of my tooth separator.

Fig. 6 represents a section on line 6—6 of Fig. 2.

Fig. 7 is a section on line 7—7 of Fig. 1.

Referring to the drawings in which like reference characters indicate like parts, and more particularly to Fig. 1, I have shown a novel tooth separator which comprises the inner jaws or separating members 8 and 9 each of which consists of the hooked or deflected member 10, which is integral with or secured to the arm 11 which terminates in a sharp point at 15. The link 14 is threadedly engaged by the screw element 16 which carries at its inner end the toggle links 18 and 19 pivoted thereto at 20. 21 and 22 designate outer jaws which are provided with the sharp points 23 and are pivoted at 24 to the toggle links 18 and 19. The jaws 21 and 22 are adapted to slide in the U-shaped brackets 25 and 26 which are secured to the arms 11 at 29. The pivots 24 connecting the toggle links 18 and 19 to the jaws 21 and 22 are adapted to slide in the slots 30 and 31 in the U-shaped brackets 25 and 26.

The operation is as follows: Referring to Fig. 1 it will be seen that I have illustrated

my device as applied to the separation of two contiguous teeth 34 and 36 with the sharp points 23 of the outer jaws 21 and 22 bearing upon the juxtaposed outer surfaces of the teeth 34 and 36 and with the sharp points 12 of the inner jaws 8 and 9 bearing upon the juxtaposed inner surfaces of the teeth 34 and 36. To separate the teeth 34 and 36 it is necessary to turn the stem 16 which forces 10 the toggle links 18 and 19 forward until the pivots 24 reach the inner ends of the slots 30 and 31. Further turning of the screw 16 results in lateral pressure exerted on the outer jaws 8 and 9, 21 and 22 to separate the points 12 and 23, thus forcing apart the teeth 34 and 36 between which the points 12 and 23 had been inserted.

In the position of the parts illustrated in Fig. 1 the jaws 8, 9, 21 and 22 are locked 20 against any movement, and to be able to adjust the spacing of the jaws 8, 9, 21 and 22, by hand, without turning the screw 16, it is necessary to turn the screw 16 to move the center 20 of the toggle connections 18 and 19 25 towards the jaws. When this has been done the jaws can be opened and closed through a predetermined range without the turning of the screw 16, so that if it is desired to separate two non-contiguous teeth 38 and 40 from one 30 or both sides of the intermediate teeth 41, the toggle link center 20 is moved away from the link 14 by turning the screw 16. This permits the jaws 8, 9, 21 and 22 to be separated by hand and particularly it permits the adjustment of the jaws 21 and 22 to the particular position of the teeth to be separated. After such adjustment has been made the screw 16 is turned to effect gradual separation as above described. In Fig. 2 I have illustrated my novel tooth separator in its position of maximum separation wherein it is shown as having separated two non-contiguous teeth 38 and 40 from an intermediate tooth 41 resulting in the space 42 on either 40 side of the tooth 41. In the position of the parts illustrated in Fig. 2 the jaws 8, 9, 21 and 22 are in their position of maximum separation and cannot be manipulated by hand, this position being the other or opposite extreme of the position shown in Fig. 2. To manipulate the jaws 8, 9, 21 and 22 by hand it is necessary that the toggle center 20 occupy a position intermediate of its positions 45 in Figs. 1 and 2. In order to effect individual adjustment of the jaws 21 and 22 before applying pressure by turning the screw 16, it is merely necessary to position the toggle center 20 in an intermediate as opposed to the extreme positions thereof so as to render the 50 jaws 8, 9, 21 and 22 manually movable.

The jaws are then fitted by hand to insure engagement of the points 12 and 23 with the teeth to be separated and when the exact position of said points has been determined the

screw 16 is turned to effect separation to the desired extent.

It will thus be seen that I have devised a novel tooth separator which constitutes a distinct improvement over my prior Patent 70 No. 1,702,869, above referred to.

Having thus described my invention what I claim as new and desire to secure by Letters Patent is:—

In a device of the character stated, a pair of inner jaws, slotted guide brackets carried thereby, a pair of outer jaws adapted to slide within said brackets, a pivoted connection common to the outer ends of said inner jaws, a screw element threadedly engaging said pivoted connection, toggle links pivotally carried by the inner end of said screw element, the other ends of said toggle links being pivotally connected to said outer jaws, the pivotal connections of said toggle links and said outer jaws engaging the slots in said brackets.

In testimony whereof I affix my signature.

CHESTER S. IVORY.
